H. THOMSON

LANDING GANGWAY

Filed June 20. 1922

FIG. 1.

FIG. 2.

UNITED STATES PATENT OFFICE.

HARRY THOMSON, OF MOTHERWELL, SCOTLAND.

LANDING GANGWAY.

Application filed June 20, 1922. Serial No. 569,726.

To all whom it may concern:

Be it known that I, HARRY THOMSON, a subject of the King of the United Kingdom of Great Britain and Ireland, and resident of Southwood, Manse Road, Motherwell, Scotland, have invented certain new and useful Improvements in Landing Gangways, of which the following is a specification.

This invention relates to ship's landing gangways and the like and has for its object to provide an improved construction of gangway which will relieve the congestion frequently arising at the entrance thereto.

According to the present invention the gangway, which may be of any usual construction, is formed with a laterally expanding end or ends, the floor of which extends in line with the gangway flooring. The entry end of the gangway is expanded laterally when in use and collapsed when the gangway is not in use or taken aboard.

In order that the invention may be more clearly understood reference is hereinafter made to the accompanying drawings showing by way of example one construction of gangway according to the present invention.

Fig. 1 is a side view of the end portion of the gangway.

Fig. 2 is a horizontal sectional view showing the end of the gangway expanded at one side only.

Fig. 3 is a vertical section taken on the line 3—3 of Fig. 2.

The gangway illustrated consists of the usual side rails 4, flooring 5 and longitudinal runners 6. The sides of the gangway terminate in posts or uprights 7 to which end sections 8 are hinged so as to turn outwardly about a vertical axis to any desired angle and thus afford more ready access to the gangway.

In Figs. 2 and 3 of the drawings only one end section is shown turned outwardly, but it will be understood that, when the gangway is in use, both end sections will preferably be turned outwardly. The flooring 5 and runners 6 of the gangway extend beyond the posts 7 and the space between the end sections 8 and the flooring 5 (when the end sections are opened out) is filled by side platforms 9 hinged to the end sections 8. The platforms 9 may be built up of timber and of substantially triangular shape hinged at 10 to the bottom runners 11 of the

end sections 8 so that, when the end sections 8 are collapsed, the platforms 9 fold up into a vertical position side by side with the end sections 8 in line with the side rails 4. 60

The end sections 8 may be guided by suitable means such as arcuate bars 12, which are rigidly secured at one end to the runners 11 respectively, and work through guide apertures 14 in the runners 6. At one end the bars 12 are provided with perforated plates 12^a for attachment to runners 11, and at the other end limiting stops 13 are provided. The bars 12 are vertically spaced, as shown in Fig. 3, in order to avoid interference. When the end sections 8 of the platform are swung outwardly (lower part of Fig. 2, and Fig. 3 at the left) this movement will be guided by the bars 12 working in apertures 14 and limited by the end 70 stops 13 when the latter come against the runners 6. 75

Claims:

1. A landing gangway having a laterally expanding and collapsible end or ends, the floor of which extends in line with the gangway flooring, substantially as described. 80

2. A landing gangway according to claim 1 having side rails terminating in vertically hinged end sections and side platforms 85 adapted to fit between the end sections and the flooring of the gangway, substantially as described.

3. A landing gangway comprising side rails, vertically-hinged end sections hinged to said side rails, flooring between said side rails and extending beyond the ends thereof and platforms carried by said end sections and adapted to fit between the latter and the flooring. 90 95

4. A landing gangway comprising side rails, flooring between said rails, runners supporting said rails and flooring, uprights at the ends of said side rails, end sections hinged to said uprights, the flooring and runners extending beyond said uprights to provide spaces between said end sections and the flooring and side platforms hinged to said end sections and adapted to fill said spaces. 100 105

The foregoing specification signed at Glasgow, Scotland, this ninth day of June, 1922.

HARRY THOMSON.
